N. J. ELDRIDGE

BOLSTER AND STANDARD CONSTRUCTION

Filed Feb. 25, 1925

FIG. 1.

UNITED STATES PATENT OFFICE.

NORMAN J. ELDRIDGE, OF GRAND ISLAND, NEBRASKA.

BOLSTER AND STANDARD CONSTRUCTION.

Application filed February 25, 1925. Serial No. 11,579.

To all whom it may concern:

Be it known that I, NORMAN J. ELDRIDGE, a citizen of the United States, and a resident of Grand Island, in the county of Hall 5 and State of Nebraska, have invented certain new and useful Improvements in Bolster and Standard Constructions, of which the following is a specification.

My invention relates to an improvement 10 in bolster and standard or stake constructions for wagons or like vehicles, and it consists in the combinations, constructions and arrangements herein described and claimed.

15 An object of the invention is the provision of a bolster and standard which is light in weight and at the same time extremely strong and durable and which may be made entirely of metal.

20 A further object of the invention is the provision of a bolster having a bearing surface of relatively great area for a bolster of a given size, the bearing surface being adapted to contact with a flat supporting 25 surface so that the bolster can turn easily on the supporting surface.

A still further object of the invention is the provision of a construction of the character described in which the standards can 30 be interchanged and replaced if desired without replacement or change of the bolster proper.

Other objects and advantages of the invention will be apparent from the following 35 description, considered in conjunction with the accompanying drawings in which:—

Figure 1 is a perspective view of the improved bolster and standard,

40 Figure 2 is a longitudinal vertical section through the bolster body, the standards being shown in side elevation,

Figure 3 is a transverse vertical section along the line 3—3 of Figure 2, and

45 Figure 4 is a transverse vertical section along the line 4—4 of Figure 2.

The bolster body is a metal channel member having a horizontal web 1 and a pair of flanges 2, the web being uppermost. The bottom edges of the flanges of the bolster body are curved convexly from end to end substantially along the arc of a circle struck by a radius of relatively great length, as best seen in Figure 2, although the bottom edges of the flanges 2 may not be truly convex from end to end in that such bottom

edges may be flattened intermediate their ends as indicated at 2^a.

The bolster body is supported midway between its ends on a bearing or turn plate 3 which is oblong in cross sectional contour and is disposed with the major axis thereof extending in the direction of length of the bolster body. The minor axis of the bearing or turn plate 3 is greater than the width of the bolster body. The bearing plate 3 is integral with an attaching member 4 which is upstanding from the bearing plate 3 along the longitudinal median line of the bearing plate, the attaching member 4 having plane vertical side walls as best seen in Figure 4 and having a width but slightly less than the distance between the inner faces of the flanges 2 of the bolster body, whereby the attaching member 4 is adapted to fit snugly between the intermediate portions of the flanges of the bolster body. The height of the attaching portion 4 is sufficient to cause said attaching portion to contact at its upper end with the lower face of the web 1 of the bolster body when the slightly flattened intermediate portions 2^a of the flanges of the bolster body rest on the bottoms of grooves 5 which are formed in the upper side of the turn plate 3 and extend longitudinally of the turn plate along the lower ends of the vertical side faces of the attaching member 4. The end walls of the attaching member 4 are preferably upwardly and outwardly inclined from their lower ends as indicated at 4^b in Figure 2, whereby the cross sectional area of the attaching member 4 increases from the lower end of the attaching member to its upper end. The attaching member 4 is secured rigidly to the flanges of the bolster body by rivets 6 or like fastening devices which extend transversely through the flanges 2 and the attaching member 4 adjacent to the end walls of the attaching member.

The web 1 is provided intermediate its length and also intermediate its width with a vertical opening 7 which is in register with a vertical opening 8 extending through the attaching member and through the turn plate 3. The openings 7 and 8 may be beveled at their opposite ends as indicated at 7^a and 8^a, respectively. The openings 7 and 8 are adapted for the reception of the usual king pin, not shown, whereby the bolster can be secured on the beam of a

wagon or like support, not shown, so that the body can turn about the axis of the king pin. The bottom or bearing surface of the turn plate 3 is indicated at 3^a and is substantially flat. Since the minor axis of the turn plate 3 is greater than the width of the bolster body, the turn plate will extend at its sides laterally of the opposite sides of the bolster body and the bolster body therefore will be turnably supported on a bearing surface of relatively great area and can turn with but very little friction and wear on its bearing surface. The upper faces of the laterally extending portions of the turn plate are convexly curved as clearly shown in the drawings.

The web 1 is formed with vertical openings 9 adjacent to but spaced from its opposite ends and located equidistant from the center of the vertical opening 7. Each of these openings 9 preferably is non-circular in cross section. A standard 10 is provided at each end of the bolster body. Each standard 10 is adapted to be projected from beneath the bolster body through one of the openings 9 until a shoulder 11 at the junction of the standard with an attaching member 12 with which the standard is integral is in abutting relation to the lower face of the web 1. The attaching member 12 for each standard 10 curves laterally from its juncture with the standard 10 and is adapted to fit snugly between the flanges 2 of the bolster body so that the bottom edge of the attaching member 12 is substantially flush with the bottom edges of the portions of the flanges 2 between which the attaching member 12 is disposed. The attaching member 12 is secured firmly to the bolster body by spaced rivets 13 or like fastening devices, which extend transversely of the bolster body through the flanges 2 and attaching members 12.

The standards 10 and the attaching members 12 with which they are integral are made of metal and the two standard and attaching member units of course are interchangeable.

Each standard 10 is provided with a plurality of vertically spaced transverse openings for the reception of pivot pins 14 which carry clevises 15 for cooperating with the standard to retain an auxiliary stake, not shown, on the adjacent end portion of the bolster body, the auxiliary stake of course being adapted to be placed on an end portion of the bolster body and extending between the clevises 15 and the adjacent end walls of the standard. Such auxiliary stake may taper from its upper to its lower end and the upper clevis 15 on each standard may be larger than the lower clevis on the standard to accommodate the downwardly tapering auxiliary stake.

From the foregoing description of the

various parts of the device, the operation thereof may be readily understood. The bolster body, the turn plate on which the bolster body is supported, the standards, and the attaching members for the standards and for the turn plate may all be made of metal. The device therefore will be compact and light in weight but also extremely strong and durable and will not wear out quickly in service. The provision of the hereinbefore described turn plate of the bolster will assure stability when the bolster is attached to an underlying support by the usual king pin while at the same time the bolster can turn with but very little friction and wear.

Obviously, the invention is susceptible of embodiment in forms other than that which is illustrated in the accompanying drawings, and I therefore consider as my own all such modifications and adaptations thereof as fairly fall within the scope of the appended claims.

I claim:

1. A bolster body comprising a metallic channel member arranged with the web thereof uppermost, and a metallic bearing member having an attaching portion extending from the upper side of the bearing member between the flanges of the channel member midway of the length of the channel member the upper face of said attaching portion abutting the lower face of the web of said channel member, said attaching portion being secured to the flanges of the channel member, said bearing member having a substantially flat lower surface and said bearing member, the attaching portion thereof and the web of the channel member being formed to provide a vertical opening for the reception of a king pin.

2. A bolster comprising a channel member having the web thereof uppermost, the bottom edges of the flanges of the channel member being curved convexly substantially along the arc of a circle from end to end, the middle portions of said bottom edges of the flanges being slightly flattened, a turn plate having parallel grooves in its upper surface for the reception of the flattened bottom edge portions of the flanges of the channel member, said turn plate having an integral attaching portion merged into the turn plate between said grooves and extending upwardly between said flanges, the upper face of said attaching portion abutting the lower face of the web of said channel member, and means securing said attaching portion to the flanges of the channel member, said turn plate, the attaching portion thereof and the web of the channel having vertical aligned openings for the reception of a king pin.

3. A bolster comprising a channel member having the web thereof uppermost, the

bottom edges of the flanges of the channel member being curved convexly substantially along the arc of a circle from end to end, the middle portions of said bottom edges of 5 the flanges being slightly flattened, a turn plate having parallel grooves in its upper surface for the reception of the flattened bottom edge portions of the flanges of the channel member, said turn plate having an 10 integral attaching portion merged into the turn plate between said grooves and extending upwardly between said flanges, the upper face of said attaching portion abutting the lower face of the web of said channel 15 member, and means securing said attaching portion to the flanges of the channel member, said turn plate, the attaching portion thereof and the web of the channel having vertical aligned openings for the reception 20 of a king pin, said attaching portion having substantially vertical side walls and being of sufficient width to fit snugly between the flanges of the channel member.

4. A bolster comprising a channel member having the web thereof uppermost, the bottom edges of the flanges of the channel member being curved convexly substantially along the arc of a circle from end to end, the middle portions of said bottom edges 30 of the flanges being slightly flattened, a turn plate having parallel grooves in its upper surface for the reception of the flattened bottom edge portions of the flanges of the channel member, said turn plate having an 35 integral attaching portion merged into the turn plate between said grooves and extending upwardly between said flanges, the upper face of said attaching portion abutting the lower face of the web of said channel 40 member, and means securing said attaching portion to the flanges of the channel member, said turn plate, the attaching portion thereof and the web of the channel having vertical aligned openings for the reception 45 of a king pin, said attaching portion having substantially vertical side walls and being of sufficient width to fit snugly between the flanges of the channel member, the ends walls of said attaching portion being inclined upwardly and outwardly from 50 their lower to their upper ends.

5. In a bolster and standard construction, a bolster body comprising a channel mem-

ber arranged with the web thereof uppermost, said channel member being formed 55 with vertical openings in its web adjacent to opposite ends thereof, and standards adapted to be extended upwardly through said vertical openings, each of said standards having an attaching portion at its 60 lower end adapted to be disposed between the flanges of the channel member and to be secured to said channel member, said attaching portion being curved to extend laterally from its juncture with the standard. 65

6. In a bolster and standard construction, a bolster body comprising a channel member arranged with the web thereof uppermost, a bearing member secured to the lower side of said channel member intermediate the ends of the channel member, said channel member being formed with vertical openings in its web adjacent to opposite ends thereof, and interchangeable standards 70 adapted to be extended upwardly through said vertical openings, each of said standards having an attaching portion at its lower end adapted to be disposed between the flanges of the channel member and to be 75 secured to said channel member, said attaching portion being curved to extend laterally from its junction with the standard and said standard and its attaching portion being formed to provide a shoulder at the lower end of the standard for abutting the underface of the web of the channel member when said standard has been extended upwardly through one of the openings in said web. 80

7. In a bolster and standard construction, a bolster body comprising a channel member arranged with the web thereof uppermost, said channel member being formed with vertical openings in its web adjacent to opposite ends thereof, and standards 95 adapted to be extended upwardly through said vertical openings, each of said standards having an attaching portion at its lower end adapted to be disposed between the flanges of the channel member and to be 100 secured to said channel member, said standard and its attaching portion being formed to produce a shoulder at the lower end of the standard abutting the underface of the web of the channel member.

NORMAN J. ELDRIDGE.
